UNITED STATES PATENT OFFICE.

FRANK CHANDLER, OF COWLEY, ALBERTA, CANADA.

KNIFE ATTACHMENT FOR TABLE-FORKS.

1,300,119.

Specification of Letters Patent.

Patented Apr. 8, 1919.

Application filed September 13, 1918. Serial No. 253,956.

To all whom it may concern:

Be it known that I, FRANK CHANDLER, of the town of Cowley, in the Province of Alberta, Canada, have invented certain new and useful Improvements in Knife Attachments for Table-Forks, of which the following is the specification.

My invention relates to improvements in knife attachments for table forks and the object of the invention is to devise an attachment whereby both the knife and fork may be operated by one hand and, therefore, adaptable for use by a man who has lost one hand and it consists essentially of the following arrangement and construction of parts as hereinafter more particularly explained.

Figure 1, is a perspective view of a fork and my attachment shown in the operative position.

Fig. 2, is a similar view to Fig. 1, showing the knife folded when not in use.

Fig. 3, is a similar view to Fig. 2, showing the knife folded in the opposite direction.

Fig. 4, is a longitudinal sectional view through the major portion of the fork and my attachment.

In the drawings like characters of reference indicate corresponding parts in the various figures.

1 indicates a fork, the shank 1^x of the handle being enlarged and provided in proximity to the head of the fork in the back with a recess 1². 2 indicates a knife blade, the edge of which is arc-shaped and is provided centrally of the back with a lever arm 2^x which fits into the recess 1² and is pivoted therein by a cross pin 2'. The arm 2^x is also provided with a notch 2². 3 indicates a sleeve which is slidable upon the handle shank 1^x, the forward lower edge portion of which engages the notch 2² when the device is in the operative position. The upper end of the lever arm 2^x is flattened and bears against a spring 4 so as to form a knife joint similar to that used in a pocket knife.

When it is desired to fold the knife the sleeve 3 is slipped up upon the shank of the knife handle so as to carry the forward edge

thereof out of engagement with the notch 2². The knife 2 is then folded back against the spring 4 into the position shown in Fig. 2. It may be desirable to fold the knife in the opposite direction or into the position shown in Fig. 3. When this is done the knife is swung up against the back of the fork and the sleeve pushed forward over the end of the arm 2^x thereby locking the knife securely in place. In this position the knife and fork are permanently carried. When it is thrown into the position shown in Fig. 2 it is merely held temporarily in this position so that it may be swung back to the operative position whenever desired.

When the knife is in use or in the position shown in Fig. 4, the fork is held in the inverted position within the hand of the operator. When the knife blade is in contact with the meat or other viual to be cut the fork is swung sidewise from side to side so that the cutting edge of the knife cuts into the substance to sever the same.

What I claim as my invention is.

1. The combination with a fork shank, of an arm hingedly connected at one end to the shank and carrying at its opposite end a knife blade set at right angles to the fork and having an arc-shaped cutting edge.

2. The combination with a fork, of a knife blade formed by a plate having an arc-shaped cutting edge, and a knife joint hinge for connecting the plate to the fork.

3. The combination with a fork, of a knife comprising a plate having an arc-shaped cutting edge, means for hingedly connecting the plate to the fork, and means for locking the plate in the operative position.

4. The combination with a fork, of a knife blade comprising a plate having an arc-shaped cutting edge, an arm extending upwardly from the back of the plate having a notch in its rear edge, means for hingedly connecting the upper end of the arm within the handle of the fork, and a sleeve slidable upon the handle of the fork and adapted to engage the notch of the knife blade at its forward edge.

5. The combination with a fork, of a knife blade comprising a plate having an arc-

shaped cutting edge, an arm extending upwardly from the back of the plate having a notch in its rear edge, means for hingedly connecting the upper end of the arm within 5 the handle of the fork, a sleeve slidable upon the handle of the fork and adapted to engage the notch of the knife blade at its forward

edge, and a knife spring bearing upon the upper end of the arm of the knife blade.

FRANK CHANDLER.
